UNITED STATES PATENT OFFICE.

FULTON R. LITTON, OF ALBUQUERQUE, NEW MEXICO.

BATH-TUB ATTACHMENT.

1,051,741.

Specification of Letters Patent.

Patented Jan. 28, 1913.

Application filed September 6, 1911. Serial No. 647,854.

To all whom it may concern:

Be it known that I, FULTON R. LITTON, a citizen of the United States, residing at Albuquerque, in the county of Bernalillo and 5 State of New Mexico, have invented new and useful Improvements in Bath-Tub Attachments, of which the following is a specification.

The present invention provides for partitioning off a bath tub, whereby the same may be adapted for bathing children, or as a foot tub, or for use as a sitz-bath, the purpose being to provide a partition which may be located at any required point in the length 15 of the tub, and means for securing the partition to the tub in the located position, the parts being so constructed as to insure a close joint between the partition and the bottom and sides of the tub and to enable 20 the device being easily and quickly placed in position and readily removed as may be desired.

The invention consists of the novel features, details of construction and combination of parts, which hereinafter will be more particularly set forth, illustrated in the accompanying drawing, and pointed out in the appended claim.

Referring to the drawing, forming a part 30 of the specification, Figure 1 is a perspective view of part of a bath tub showing the invention applied thereto. Fig. 2 is a side view of the attachment, the dotted lines showing pivotal movement of the hooks and 35 the operation of the cast off. Fig. 3 is a section on the line $x-x$ of Fig. 2. Fig. 4 is a sectional view on the line $y-y$ of Fig. 2. Fig. 5 is a view similar to Fig. 4 of a modification.

40 Corresponding and like parts are referred to in the following description, and indicated in all the views of the drawing, by the same reference characters.

The numeral 1 designates a bath tub of 45 the type provided with a rolled rim. The device comprises a partition 2 and a securing bar 3. The partition 2 is of a size to fit within the tub and to conform to the outline thereof so as to cause its lower and vertical edges to engage with the bottom and sides of the tub. A yieldable edge 4 is fitted to the bottom and sides of the partition and insures a close joint with the corresponding parts of the tub to prevent the 55 escape of water from one side of the partition to the other. The yieldable edge 4 is

to be made either of rubber or pneumatic flexible tube, sufficiently yieldable to conform to the outline of the tub to insure a close joint. The partition may be of any 60 material, either metal or wood, and the yieldable edge 4 may be secured in place thereto in any manner. The securing bar 3 is adapted to be connected at its ends to opposite sides of the tub and for this purpose 65 hooks 5 and 6 are hingedly connected at their lower ends to the bar 3 and their hooked ends are adapted to engage over the rim of the tub. The hook 6 has an inner extension 7, which engages under the roll at 70 the upper edge of the tub, thereby preventing vertical displacement of the hook or the bar attached thereto. A cast-off 8 is hingedly connected to the hooked end of the hook 5, which is flexible to admit of 75 the projection 9 formed by the hinge joint springing under the rolled rim of the tub to hold the hook 5 in place, thereby preventing casual upward movement of the bar 3. The cast-off 8 is adapted to extend beneath the 80 rolled rim of the tub and to engage a side of the tub, thereby being out of the way. An extension 10 of the cast-off overhangs the rolled rim of the tub and is adapted to operate through a slot formed in the hook 5. 85 When pulling outward upon the lower end of the cast-off 8 the extension 10 is caused to bear against the rolled rim of the tub, thereby springing the projection 9 from beneath the lower edge of the rolled rim and 90 lifting the hook 5 upward and starting the partition which may be easily removed. After the hook 5 has been disengaged from the rolled rim of the tub the partition may 95 be lifted at one end, whereby the hook 6 may be easily disengaged from the rolled rim of the tub to admit of the partition being lifted from the tub to be laid aside or to be adjusted to a new position as required.

Guide means is provided between the securing bar and the partition to hold the latter in place. A pair of arms 11 are pendent from the securing bar near each end thereof and pass through keepers 12 located upon the sides of the partition 2 near the upper 100 corners thereof. The lower ends of the arms 11 have outer extensions 13 which engage the lower edges of the keepers 12 to prevent slipping of the arms 11 from the keepers. Eccentrics 14 are mounted in the 105 upper portions of each pair of arms 11 and are adapted to engage the upper edge of the 110

partition 2 whereby the latter may be forcibly moved downward after the securing bar 3 has been fastened to insure a close joint between the partition and the tub.

5 For convenience of turning the eccentrics 14 finger pieces 15 are attached to extensions of one of the journals.

When a part of the bath tub is required to be partitioned off to suit any condition 10 the securing bar 3 is placed in position and made fast by engaging the hooks 5 and 6 beneath the rolled rim of the tub, after which the eccentrics 14 are turned to press the partition downward to cause the yield- 15 able edge 4 thereof to make a close joint with the bottom and sides of the tub. This enables any part of the tub to be partitioned off so that economy in the use of water may be attained while the tub is adapted for 20 bathing children, the feet, or for indulging in a sitz-bath. When it is required to move the partition the eccentrics 14 are turned to relieve the pressure upon the partition, after which the cast-off 8 is operated to release 25 the hook 5 when the end of the partition corresponding to the position of the hook 5 is lifted, thereby releasing the hook 6 from the rolled rim of the tub so that the partition and securing bar may be lifted from the 30 tub.

From the foregoing description, taken in connection with the accompanying drawing, the advantages of the construction and of the method of operation will be readily apparent to those skilled in the art to which 35 the invention appertains, and while I have described the principle of operation of the

invention, together with the device which I now consider to be the embodiment thereof, I desire to have it understood that the device shown is merely illustrative, and that such changes may be made when desired as are within the scope of the claim appended hereto.

In the modification shown in Fig. 5 the 45 partition 2^a is solid, preferably of wood, and has a pneumatic edge 4^a, the latter consisting of a tube seated in a groove formed in the edge of the partition.

Having thus described the invention what 50 is claimed as new, is:-

Means for partitioning a bath tub having a rolled rim, the same consisting of a bar to extend across the tub, a hook pivotally connected to one end of the bar and 55 having an inner extension to engage under the rim of the tub, a second hook pivotally connected to the opposite end of the bar and having its outer end longitudinally slotted, a cast off pivotally connected to the slotted 60 end of the hook and having an extension to operate through the slotted end of the hook to engage the rim of the tub, the hinge between the cast off and slotted hook extending inwardly to engage beneath the rim of 65 the tub, a partition, and means carried by the bar for pressing the partition home within the tub.

In testimony whereof I affix my signature in presence of two witnesses.

FULTON R. LITTON.
